UNITED STATES PATENT OFFICE.

JOHN L. KELLEHER, OF LE MARS, IOWA.

WRINGER-SUPPORT.

1,161,390.

Specification of Letters Patent. Patented Nov. 23, 1915.

Application filed May 27, 1912. Serial No. 700,013.

To all whom it may concern:

Be it known that I, JOHN L. KELLEHER, a citizen of the United States, residing at Le Mars, in the county of Plymouth and State of Iowa, have invented certain new and useful Improvements in Wringer-Supports, of which the following is a specification, reference being had therein to the accompanying drawing.

This invention relates to clothes wringers, and has for its object the production of an efficient wringer attachment whereby the wringer may be swung to different positions with reference to a washing machine so as 10 to deliver the articles from one tub to another.

Another object of this invention is the production of an efficient means whereby the belt for driving the wringer will be held so 20 as to operate the wringer when the wringer is swung to several adjusted positions.

With these and other objects in view this invention consists of certain novel constructions, combinations, and arrangements of 25 parts, as will be hereinafter fully described and claimed.

In the drawings, Figure 1 is a top plan view of the machine. Fig. 2 is a side elevation thereof. Fig. 3 is a section taken on 30 line 3—3 of Fig. 2. Fig. 4 is a detail perspective of the upper journal bolt which constitutes a pivot for the frame which supports the wringer. Fig. 5 is a detail perspective of one of the adjusting members 35 carried by the pivot bolt illustrated in Fig. 4. Fig. 6 is a detail perspective of the arm, whereby the wringer may be lifted so as to tighten the belt which drives the wringer rollers. Fig. 7 is a diagrammatic view of 40 the arrangement of the washing machine with reference to the rinsing and bluing tubs.

The present device is especially adapted to be attached to a washing machine which 45 comprises a body 1, which is mounted upon the usual legs or standards 2. The usual top 3 is hinged to the support 4 carried by the upper end of the body 1, and this cover 3 is hinged to the support 4 by means of the 50 hinges 5. One of the hinges 5 also constitutes a bearing for the clothes agitating shaft 6, which shaft is also supported by means of a journal box 7. A bracket 8 is secured to the cover and is pivotally mounted on the shaft 6, said bracket having a lat-

erally extending arm 9, carrying a roller 10, which roller acts as a belt tightening means for the belt 11. A pulley 12 is carried by the shaft 6 and the belt 11 passes over this pulley and also passes over a pulley 13 carried by the main drive shaft 14. 60

An eccentric arm 15 is carried by the inner end of the shaft 6, and to this arm is connected a link 16, which link in turn engages a rack bar 17, said rack bar passing through 65 guide brackets 18. A gear wheel 19 is journaled in the lid or cover 3, and to this gear wheel is connected the usual clothes agitator which may be made of any desired type.

The drive shaft 14 at one end carries a 70 main drive pulley 20 which drive pulley receives a drive belt from the engine or other driving mechanism, and this shaft 14 is supported upon the legs or standards 2, by means of brackets 21. The opposite end of 75 the shaft 14 carries a pulley 22, and over this pulley 22 passes a belt 23, which belt in turn engages a pulley 24 carried by the shaft 25, which shaft constitutes the main drive shaft for the wringer 26. 80

A bracket 27 is carried by one of the standards or legs 2 as indicated in Fig. 2, and this bracket is provided with a pair of parallel arms 28, which arms are connected at their outer ends by means of a shaft 29. A 85 bracket 30 is provided with an angle foot 31, which foot encircles the shaft 29, and is capable of having longitudinal movement upon the shaft 29. The upper end of the bracket 30 is provided with an angle extension 32 90 which angle extension engages the wringer supporting arm 53, as indicated in Fig. 2.

A metallic brace or overhanging arm 33 is carried by the upper end of the body 1. This overhanging arm 33 comprises a pair 95 of converging arms 34, and the lower end of this overhanging arm 33 is secured to the body 1 by means of rivets or other securing means 35. Enlarged portions 36 are formed upon the arm 33 and in these enlarged portions 36 are secured the free ends of the metallic band 37 which encircles the body 1 and assists in holding the bracket or arm 33 in engagement with the body 1. 100

The outer end 41 of the arm 33 is apertured so as to receive the vertically extending cylindrical lower end 40 of bolt 38 which is carried by the upper end 54 of the angle arm 53 which carries the wringer 26. 105

An elevating arm 42 is carried by the cy- 110

lindrical portion 40 of the journal bolt 38 upon which cylindrical portion it is rotatably mounted, and this arm 42 has a head which is provided with beveled sides 43, which sides terminate in a flat body portion 44. A stop washer 45 is slidably mounted upon the journal bolt 38, and this washer 45 comprises a collar portion 46, and a pair of laterally extending fingers 47. These fingers 47 are adapted to fit upon the upper edges of the beveled sides 43 of the head of the arm 42 when the arm is in one position and the fingers 47 are adapted to rest upon the flat body portion 44 when the arm 42 is in a position at right angles to that shown in Fig. 2. The collar portion 46 is provided with a rectangular aperture 48 for holding the washer 45 against rotation. Two sides of the collar 46 are beveled as indicated at 49 for allowing the washer to fit snugly in engagement with the flat portion 44 of the arm 42. The upper end of the journal bolt 38 is provided with a threaded portion 50 which receives a thumb nut 51, and between the washer 45 and thumb nut 51 is positioned a coil spring 52.

The wringer 26 is mounted on an outwardly extending arm 53 which arm is provided with an angularly extending end 54 to which is integrally secured the journal bolt 38, above-mentioned. The angularly extending end 54 of the bracket or arm 53 is provided with a web portion 55 for reinforcing the angle end 54 of the bracket or arm 53. The wringer 26 of the ordinary construction is associated with the arm 53 as above stated and this wringer carries the usual wringer rollers 56. The shaft 25 carries gears 57, which mesh with gears 58 carried by the upper wringer roller as indicated in Fig. 2. The wringer may, if so desired, be operated by means of a crank 59 which is connected to the end of one of the gears 57 by means of a clutch 60. The arm 53 is provided with an ear 61, and to this ear 61 is pivotally secured a locking lever 62. The lower end of the lever 62 is normally held in engagement with a rack segment 63 by means of a coil spring 64. The rack segment 63 is provided with a plurality of notches 65, and this segment is se-

curely held to the body 1, by means of rivets or other securing means 66.

As illustrated in Figs. 1 and 2, it will be seen that the wringer 26 may be swung in alignment with the shaft 14 or may be swung at right angles thereto, as indicated in the diagram in Fig. 7. The wringer is held in its adjusted position by means of the latch lever 62, as above described. When the wringer 26 extends in alignment with the shaft 14, the lifting lever or arm 42 is swung so that the fingers 47 will rest upon the upper ends of the beveled sides 43 which will cause the belt 23 to be tightened so as to easily operate the wringer rollers 56. When the wringer 26 is swung at right angles to the shaft 14, or the position shown in the diagram in Fig. 7, the lever or arm 42 may also be swung so as to allow the fingers 47 of the washer 45 to fit upon the flat portion 44 of the head of the arm 42, thereby lowering the wringer 26 to a certain extent to allow for the take-up of the belt 23. As this wringer 26 has vertical sliding movement, the angle end 31 will in turn slide on the shaft 29.

By having the wringer so that the same may be swung to different positions, it will be seen that the clothes can be wrung from the bluing tub so that the same may pass into the rinsing tub, or vice versa, especially since the tubs may be arranged in the position as indicated in the diagram in Fig. 7.

What is claimed is:—

A wringer support comprising an overhanging bracket, an angle arm carried by said bracket, said angle arm adapted to support a wringer, a bracing bracket secured to the bottom of said angle arm, a journal bolt carried by said angle arm and extending through the upper end of said overhanging bracket, said bolt constituting a pivot point for said angle arm and means for locking said angle bracket in a set position against swinging movement.

In testimony whereof I hereunto affix my signature in presence of two witnesses.

JOHN L. KELLEHER.
